UNITED STATES PATENT OFFICE

100,883

DESIGN FOR A TANK VEHICLE

Frederick G. Thwaits, Wauwatosa, Wis., assignor
to The Heil Co., Milwaukee, Wis., a corpora-
tion of Wisconsin

Application May 8, 1935, Serial No. 56,727

Term of patent 14 years

To all whom it may concern:

Be it known that I, Frederick G. Thwaits, a citizen of the United States, residing at Wauwatosa, in the county of Milwaukee and State of Wisconsin, have invented a new, original, and ornamental Design for a Tank Vehicle, of which the following is a description, reference being had to the accompanying drawing forming part thereof.

In the drawing:

Fig. 1 is a side elevation of a motor truck embodying my new tank vehicle design; and

Fig. 2 is a rear view of the tank vehicle.

The characteristic features of the present de-

sign reside in the substantially continuous and uninterrupted merging of the cab and tank sections, in the sweeping longitudinal curvature of the top and rear upper portions of the tank section and catwalks, and in the curvature of the lowermost trailing portions of the rear fenders, catwalks, and tank end. The dominant or characteristic features of the design are shown in solid lines, and the unimportant features are shown in dotted lines.

I claim:

The ornamental design for a tank vehicle, substantially as shown and described.

FREDERICK G. THWAITS.
